UNITED STATES PATENT OFFICE.

HUGO L. HILLER, OF NEW YORK, N. Y.

LACING-TIP.

No. 835,824.

Specification of Letters Patent.

Patented Nov. 13, 1906.

Application filed March 31, 1905. Serial No. 253,053.

To all whom it may concern:

Be it known that I, HUGO L. HILLER, a citizen of the United States, and a resident of the borough of Manhattan, in the city and 5 State of New York, have invented a new and useful Improvement in Lacing-Tips, of which the following is a specification.

The object of this present invention is to provide a lacing-tip which will be tapered and also reinforced in its interior, so that the tip may be readily passed through small eyelets without causing the tip to bend or become frayed at its point.

A further object is to provide a lacing-tip 15 in which the reinforcement is located entirely within the tip and the tip so shaped as to give a very attractive appearance to the lacing.

A practical embodiment of the invention is 20 represented in the accompanying drawings, in which—

Figure 1 represents the end of a lacing-body with a tapered metallic reinforcement in position thereon, showing the first step in 25 the formation of the lacing-tip. Fig. 2 is a similar view showing the second step in which the corners of the lacing-body are removed. Fig. 3 is a similar view showing the third step—viz., the end of the lacing-body 30 folded over the smaller end of the tapered reinforcement. Fig. 4 is a similar view showing the fourth step—viz., the folding of one side of the lacing-body over one side of the tapered reinforcement. Fig. 5 is a similar 35 view showing the fifth step—viz., the folding of the other side of the lacing-body over the corresponding side of the reinforcement. Fig. 6 is a similar view showing the sixth step—viz., the first interlocking fold of the 40 lacing-body and reinforcement. Fig. 7 is a similar view showing the second interlocking fold of the lacing-body and reinforcement. Fig. 8 is a similar view showing the completed tapered tip after the interlocked folds 45 of the lacing-body and reinforcement have been crushed into a solid mass. Fig. 9 shows the tapered reinforcement in end view and top plan before it has been folded. Fig. 10 shows the reinforcement in end view and top

plan after its first fold. Fig. 11 shows the 50 reinforcement in end view and top plan after the second fold, and Fig. 12 is an exaggerated cross-section through the completed tip.

The body of the lacing is denoted by 1. A 55 tapered reinforcement 2 is provided, which reinforcement is preferably made of sheet metal capable of being readily bent as may be desired to complete the tip. The corners of the end of the lacing-body are cut off, as 60 shown at 3 and 4, Fig. 2. The end of the body is then folded over the smaller end of the reinforcement 2, as shown at 5, Fig. 3. One side of the lacing-body is then folded over one side of the reinforcement, as shown 65 at 6, Fig. 4. The other side is then similarly folded over, as shown at 7, Fig. 5. The sides of the reinforcement at its wide end are then folded toward each other, together with the folded-over portions 6 and 7 of the lacing- 70 body, to form the first interlocked fold, as shown at 8 and 9, Fig. 6. The reinforcement and the lacing-body are then folded together again, as shown at 10 and 11, Fig. 7. The interlocked folds of the tapered reinforcement and the tapered end of the lacing- 75 body are then crushed together into a solid mass to form the completed tapered tip designated at 12, Fig. 8.

The exaggerated view in cross-section of 80 the completed tip which is shown in Fig. 12 will give an idea of how the interlocked folds of the lacing-body and reinforcement are crushed into a solid mass.

What I claim as my invention is— 85

The combination with a lacing, of a tapered metallic reinforcement at the end of the lacing, the said reinforcement and lacing being crushed into a tapered, solid mass presenting a non-metallic exterior surface. 90

In testimony that I claim the foregoing as my invention I have signed my name, in presence of two witnesses, this 27th day of March 1905.

HUGO L. HILLER.
